[57] CLAIM

The ornamental design for a bicycle pedal tread, as shown and described.

DESCRIPTION

FIG. 1 is a top perspective view of a bicycle pedal tread showing our new design.

FIG. 2 is a front elevational view thereof.

FIG. 3 is a top plan view, the bottom plan view of which is a mirror image thereof.

FIG. 4 is an end elevational view of one end, the opposite end of which is a mirror image thereof.

FIG. 5 is a rear elevational view thereof.

FIG. 6 is a top perspective view of a second embodiment of a bicycle pedal tread showing our new design.

FIG. 7 is a front elevational view of the embodiment of FIG. 6.

FIG. 8 is a top plan view of the embodiment of FIG. 6, the bottom plan view of which is a mirror image thereof.

FIG. 9 is an end elevational view of one end of the embodiment of FIG. 6, the opposite end of which is a mirror image thereof.

FIG. 10 is a rear elevational view of the embodiment of FIG. 6.
